UNITED STATES PATENT OFFICE.

THOMAS M. EYNON, OF PHILADELPHIA, PENNSYLVANIA.

HIGH-SPEED STEAM AND AIR BLOWER.

Application filed June 11, 1921. Serial No. 476,845.

My invention relates to blast devices intended to combine the advantages of steam injectors and fans for the cheap and effective supply of air under pressure for forced draft in furnaces.

The main purpose of my invention is to increase the efficiency of the device at the same time that the supply of moisture is reduced.

10 A further purpose is to supply air under pressure to a preferably live steam air-injector system.

A further purpose is to furnish a supply of air under pressure through a manifold 15 to a plurality of furnace forced draft inlets and to accelerate the speed of air delivery at these individual points as they may be separately required and at the same time add desirable moisture thereto by a live steam 20 air injector in each connection from the manifold.

Further purposes will appear in the specification and in the claims.

My invention is intended to relate to the 25 processes involved as well as to mechanism by which these processes may be carried out.

I have preferred to illustrate my invention by but one form of separate air and steam units for forced draft feed and but one form 30 of combination units having air manifold supply for injectors, selecting forms which are practical, efficient, inexpensive and above all reliable and which at the same time well illustrate the principles of my invention.

35 Figure 1 is a longitudinal section showing a preferred form of a single unit fan and high pressure steam injector.

Figure 2 is an end elevation of the fan.

40 Figure 3 is a longitudinal section of a manifold and connections.

In the drawings similar numerals indicate like parts.

I am aware of the fact that injectors have been used in connection with fans for supplying forced feed of air to furnaces. A 45 patent upon one of these devices was taken out by me May 16, 1916, No. 1,182,665, in conjunction with Messrs. Paine and Murphy. However, in this patent reliance was placed 50 upon exhaust steam rather than live steam, giving a relatively high percentage of moisture per unit of air delivered, the fan received the blast from the injector and both the fan and the injector were of low enough 55 efficiency to seriously affect their combination for the purpose intended. The fan was

of what might be called a "volume" type as contradistinguished from a "pressure" type.

Each of the changes made from this construction to my present form is advantageous 60 and their combination is particularly so.

Describing the forms of the present invention by way of illustration and not in limitation:—

I combine a fan of very high efficiency and 65 preferably of the pressure type, shown at 5 with a highly efficient live steam injector 6 to which the air from the fan is led, giving a relatively high pressure and full volume of air at the rear of the injector and upon 70 which the injector operates as its supply.

The form of fan which I prefer to use, 75 on account of its very high efficiency and because of the relatively large diameter and high velocity of the cylinder of air delivered by it, is that upon which Patent No. 1,372,755 issued to Messrs. Kamp and Macmechan, having its operating blades forming tangents to the radii about which the blades are bodily revolved. I show three blades, 80 7, 8 and 9, supported upon shaft 10 by rods 11 which are connected to the shaft at 12 and 13 and are connected to the blades at any points 14 and 15. The shaft is mounted in bearings not shown and is preferably 85 rigid with the shaft of a motor 16 here shown as an electric motor. Any suitable mounting 17 may be used for the motor and for its shaft.

The fan is mounted within a casing 18 90 which affords an inlet to a chamber 19, within which is located a live steam injector. This injector is shown as comprising any number of nozzles 20, 21, 22, 23, 24 discharging each within the flared rear end 25, 26, 95 27, 28, 29, of the next nozzle in advance thereof and the final nozzle communicating with a delivery tube 30 connected with the furnace beneath the grate. The inlets are shown at 31, 32, 33, 34, 35.

An injector is fed by a live steam pipe 36 controlled by any suitable valve 37.

It will be evident that a fan of the character indicated having its effective blade surfaces located wholly at some distance from the shaft about which they revolve will drive the air from the point at which it leaves the blades, discharging it initially within the space represented by a cylinder having a radii thickness equal to the difference between the inside and outside radii of the blades and an inside diameter equal to the 100 105 110 115

inside diameter of the blades. The kinetic energy of the flow about this annulus will be exerted primarily upon the larger intake openings of the injector (those at the left hand end in Figure 1) because it corresponds most nearly in radius with the radii of these openings. The effect of this will be to reduce the fluid friction upon the air which is driven the longest distance before being taken into the injector and to furnish this air to the injector at substantially the same pressure as that at which it leaves the fan, equalizing the pressure to a large extent over all of the injector inlets and feeding the air freely at pressure within those inlets farthest from the fan and which by reason of the larger diameter at this point offer intake for the largest quantity of air.

In operation, the high efficiency and pressure fan drives the air to the various intakes so that the air is not dependent upon the steam flow alone for induction into the injector but is forced into it by the pressure of the air. This in connection with the high pressure steam flow through the injector gives a much more effective air flow for a given quantity of steam inlet, reducing the moisture content to a minimum and at the same time securing a maximum of efficiency in the quantity of air delivered for the energy expended.

In the form shown in Figure 3 a single fan is used in connection with a number of furnaces, delivering its blast of air into a manifold 40 from which it may be directed into separate supply pipes 41, 42, 43 or any of them by opening corresponding valves, here typified as butterfly valves 44, 45, 46.

I locate the individual injectors 6', 6², 6³ within the supply pipes 41, 42, 43 and feed 40 the steam, preferably live steam to them through pipes 31', 31², 31³.

In operation the air under pressure within the manifold is supplied to the individual injectors through the butterfly valves as they are opened and the steam is turned on the injectors to add the injector drive to the air blast.

It will be obvious that all or a part of my invention may be presented in other forms, 50 as appeals to the whim or need of those skilled in the art; and it is my purpose to include all such forms within my invention as come within its reasonable spirit and scope.

Having thus described my invention, what I claim as new and desire to secure by Letters Patent is:—

1. In a draft system for furnaces, a casting, a live steam injector therein, adapted to entrain air having inlet openings increasing in size in the direction of steam travel, in combination with a fan supplying air to the injector under pressure and in a hollow cylindrical column comparable in diameter 65 to that of the larger inlet openings.

2. In a draft system for furnaces, a casting, a live steam injector therein, adapted to entrain air and having a series of air inlets of cross-section increasing as they approach the discharge end of the injector, in combination with a fan having tangentially arranged blades discharging air to the injector.

THOMAS M. EYNON.
